UNITED STATES PATENT OFFICE.

JOSEPH E. KENNEDY, OF NEW YORK, N. Y.

CRUSHING AND PULVERIZING MACHINE.

1,143,203.

Specification of Letters Patent. Patented June 15, 1915.

Application filed February 2, 1914. Serial No. 815,929.

To all whom it may concern:

Be it known that I, JOSEPH E. KENNEDY, a citizen of the United States, and a resident of the borough of Manhattan, city, county, and State of New York, have invented certain new and useful Improvements in Crushing and Pulverizing Machines, of which the following is a specification.

10 My invention relates to the type of crushing and pulverizing mechanism in which a gyratory shaft is journaled at its lower extremity in an eccentric bearing seated in a rotatable sleeve, as set forth in my current application Serial No. 703,178 filed June 12th, 1912, patented Nov. 3d, 1914, No. 1,115,833, in which I insure the rotation of the eccentric bearing with the sleeve in which it is seated by means which allow the 15 eccentric bearing to adapt itself to the inclination of the gyratory shaft,—the object being to obviate as far as possible wear between the contacting surfaces of the interlocking parts by which the eccentric bearing and rotatable sleeve are so coupled together, as hereinafter fully set forth. This is effected by means of a coupling pin mounted on one of said parts and formed with an elongate head protruding into a 20 longitudinal recess in the other part,—said head having an extensive bearing surface which obviates the danger of its seating itself in the side wall of the recess. In said concurrent application the coupling pin and its head are integral and the pin is loosely seated in its part so as to admit of its turning therein to allow the eccentric to adapt itself to the inclination of the shaft. In the present case the rectangular head of the 25 coupling pin is loose thereon to admit of and compensate for the movement of the eccentric bearing within its seat in the rotatable sleeve, and prevent the head from wearing itself into the side of the recess against which it bears,—the frictional 30 resistance between the contacting surfaces being thus reduced to the minimum by the ease with which the loose head of the coupling bolt responds to any variation in inclination between the eccentric bearing and driving sleeve.

One advantage of my present construction of loose head on the coupling pin over the loose pin described and claimed in my Letters Patent No. 1,115,833, hereinbefore referred to, is that the creeping of the lining

of the eccentric bearing, or of the eccentric bearing itself with relation to said lining when used, tends to pinch and hold the coupling pin and its head rigidly thereby 60 increasing frictional strain and wear, whereas in the present case the head is free to turn under all conditions of use whether the pin be held rigid or not.

By mounting the coupling pin head 65 loosely on the coupling pin the latter may be made much smaller in diameter and be driven in tightly to form a permanent integral part of that to which it is thus attached, while the head may be reversed (as 70 only one side bears against the opposed side of the recess in ordinary use), or removed entirely and another substituted when desirable, without disturbing the coupling pin. Furthermore the wear of 75 the pin on the inner surface or bore of the head does not affect the utility of the latter's bearing contact with the side of the recess; and finally, the wear of the pin on the part in which it is inserted is obviated by this my 80 present construction and arrangement of parts.

In the accompanying drawings, Figure 1, is a central vertical sectional elevation of the lower portion of a gyratory crusher of 85 the type to which my invention is applicable. Fig. 2, is a horizontal section taken upon plane of line 2—2 Fig. 1; Fig. 3, shows the several details of the coupling pin and slot upon a larger scale; Fig. 4, shows an 90 alternative or modified construction of interlocking parts.

In general construction and operation the apparatus is essentially the same as heretofore known and used, A, representing the 95 gyratory shaft upon the upper part of which the usual truncated conical crusher head is supported in an oppositely inclined conical crushing chamber.

The lower portion of the gyratory shaft 100 A, is journaled in the bore b, of the eccentric bearing B, which is formed with a convex peripheral surface b', seated in a corresponding concavity s, in the rotatable sleeve S, to which the driving gear d, is secured,—said driving gear d, being rotated 105 by the pinion p, on the power shaft P.

In order to insure the rotation of the eccentric bearing B, with the sleeve S, and at the same time allow it to conform to the 110 inclination of the longitudinal axis of the gyratory shaft S, it is necessary to couple

the eccentric bearing B, and the sleeve S, together by means which will allow the convex peripheral surface b' , of the eccentric bearing B, to rock vertically on the concave seat s , of the sleeve S, and in order to accomplish this in a simple and effective manner I provide on one part a coupling pin c , the protruding elongated rectangular head c' , of which engages with a side wall of a longitudinal recess r , in the other part.

By preference I form the longitudinal recess r , in the sleeve S, opening into the concave seat s , and drive the shank of the pin c , into a socket b^2 , formed for its reception in the eccentric bearing B, as shown in Figs. 1, 2 and 3 of the accompanying drawings, although it is obvious that the alternative arrangement may be resorted to without departing from the spirit and intent of my invention in this respect. That is to say as an equivalent mechanical expedient the longitudinal recess r , may be formed in the eccentric bearing B, and the coupling pin c , be attached in the sleeve if desired with like result as shown in Fig. 4. The important feature in this connection is the formation of the coupling pin c , with a loose preferably elongate rectangular head c' , affording an extensive bearing surface for contact with a side of the longitudinal slot, thereby equalizing and distributing the wear, and lengthening the life and utility of the bearing. In other words I counteract the tendency of the head of the coupling pin to augment frictional resistance or possibly even eventually render the ball and socket joint inoperative, by wearing a seat for itself in the opposed wall surface of the longitudinal coupling slot.

In my concurrent application hereinbefore referred to the body or shank of the coupling pin is seated loosely, for instance, in a socket b^2 in the eccentric bearing B, and bears the brunt of the twist motion, which necessitates making the pin c , and its socket b^2 , of large diameter, whereas by making the head c' , loose as in the present case I am enabled to use a pin of comparatively small diameter and drive it permanently into the eccentric bearing B, to form an integral part thereof thereby relieving the latter of pin wear which is all transferred to the loose head c' , made of suitable size and shape to sustain frictional contact with the side of the recess r , in the sleeve, without wearing a seat for itself therein.

If the loose head c' , is made of elongated rectangular form it is obvious that the elongated parallel sides will each form a possible bearing surface for contacting with the side wall of the recess r , so that by reversing the head when one side is worn, double service may be had; and it is also obvious that by making the head c' , square and of proper dimensions, with a recess of

corresponding width, the wear may be quadrupled. And in any event a new head c' , may always be substituted for an old one without extracting or disturbing the pin c .

What I claim as my invention and desire to secure by Letters Patent is,

1. In crushing mechanism of the character designated, the combination of a gyratory shaft, means for supporting the same, an eccentric bearing for the lower portion of said shaft rotative about said shaft to cause its gyratory movement, said eccentric bearing having a convex peripheral surface, a rotatable sleeve formed with a concavity in which the eccentric bearing is seated, said sleeve being also formed with a longitudinal recess in said concave seat, a coupling pin fitting in a socket formed for its reception in said eccentric bearing, said pin being formed with a loose head protruding into the longitudinal recess in the sleeve and having an extensive bearing surface contacting with a side thereof, whereby the positive rotation of the eccentric bearing with the sleeve is insured while permitting the bearing to adapt itself axially to the inclination of the shaft, and means for rotating said sleeve.

2. In crushing mechanism of the character designated, the combination of a gyratory shaft, means for supporting the same, an eccentric bearing for the lower portion of said shaft rotative about said shaft to cause its gyratory movement, said eccentric bearing having a convex peripheral surface, a rotatable sleeve formed with a concavity in which the eccentric bearing is seated and also formed with a longitudinal recess in said concave seat, said recess having an elongate flat surface parallel to the longitudinal axis of the eccentric bearing, a coupling pin fitting in a socket formed for its reception in said eccentric bearing, said pin being formed with a loose head protruding into said longitudinal recess in the sleeve and having an extensive flat bearing surface for contacting with the bearing surface of the longitudinal recess in the sleeve, whereby the eccentric bearing is permitted to adapt itself axially to the inclination of the shaft while rotating positively with the sleeve, and means for rotating said sleeve.

3. In crushing mechanism of the character designated, the combination of a gyratory shaft, means for supporting the same, an eccentric bearing for the lower portion of said shaft rotative about said shaft to cause its gyratory movement, said eccentric bearing having a convex peripheral surface, a rotatable sleeve formed with a concavity in which the eccentric bearing is seated, and means for coupling said eccentric bearing and said sleeve together in such manner that they will rotate together while admitting the eccentric bearing to adapt itself to the axial inclination of the gyratory shaft, said

means consisting of a coupling pin mounted on one part and formed with a loose head protruding into a longitudinal recess in the other part and having an extensive bearing surface contacting with the longitudinal bearing surface of the recess.

4. In crushing mechanism of the character designated the combination of a gyratory shaft, means for supporting the same, an eccentric bearing for the lower portion of said shaft rotative about said shaft to cause its gyratory movement, said eccentric bearing consisting of a plurality of members, one member having a convex peripheral surface, another of said members being a rotatable eccentric sleeve formed with a concavity in which said first named member is seated, and also formed with a longitudinal recess in said concave seat, a coupling pin in a socket formed for its reception in said first named member, said pin being formed with a loose head protruding into the longitudinal recess in the sleeve, said loose head having a bearing surface contacting with the side thereof whereby the positive rotation of the first named member with the sleeve is insured while permitting the bearing to adapt itself axially to the inclination of the shaft, and means for rotating said sleeve.

5. In crushing mechanism of the character 30 designated, the combination of a gyratory shaft, means for supporting the same, an eccentric bearing for the lower portion of said shaft rotative about said shaft to cause its gyratory movement and in which said 35 shaft is movable longitudinally, said eccentric bearing consisting of a plurality of members one member having a convex peripheral surface, another of said members being a rotatable eccentric sleeve formed 40 with a concavity in which said first named member is seated, and means for coupling said first named member and said sleeve together in such manner that they will rotate together while admitting the first named 45 member to adapt itself to the axial inclination of the gyratory shaft, said means consisting of a coupling pin mounted on one member and formed with a loose head protruding into a longitudinal recess in the 50 other member and having an extensive bearing surface contacting with the longitudinal bearing surface of the recess.
